UNITED STATES PATENT OFFICE.

JOHN P. WOLF AND GEORGE IFFLAND, OF CHICAGO, ILLINOIS.

TABLE-LEAF SUPPORT.

SPECIFICATION forming part of Letters Patent No. 331,857, dated December 8, 1885.

Application filed September 8, 1884. Serial No. 142,540. (No model.)

To all whom it may concern:

Be it known that we, JOHN P. WOLF and GEORGE IFFLAND, residing at Chicago, in the county of Cook and State of Illinois, and citizens of the United States, have invented a new and useful Improvement in Table-Leaf Supports, of which the following is a full description, reference being had to the accompanying drawings, in which—

10 Figure 1 is a vertical section showing the table-leaf down. Fig. 2 is a section at line α of Fig. 1, looking to the right. Fig. 3 is a section through a table at the point y with the leaf open, the support being shown mostly in elevation. Fig. 4 is an under side view with the leaf open. Fig. 5 is a modification. Fig. 6 is a modification. Fig. 7 is a detail.

15 The objects of our invention are to provide a table leaf support which will be self-acting when the leaf is opened, which can be easily released to let the leaf down, which will prevent the hinges from being strained by raising the leaf too high, and which will hold the leaves securely in position when two tables are put together for shipping with the leaves open, as is customary, which we accomplish as illustrated in the drawings, in which—

20 A represents the top of a table; B C, an end and a side piece of the frame; D D', two short braces to support the piece C.

25 E is a table-leaf.

a is an opening or slot in the piece C.

30 b is a piece of metal secured to the under edge of C, over the opening a.

35 F is a casting, which supports the leaf when open. One part of this casting, e, is curved from the free end to the bend d, as shown in the drawings, and is strong. The remaining portion of the casting, e, is somewhat thin and 40 broad, so that it can have a little spring action. One end of the casting F is pivoted to the under side of the leaf E. This can conveniently be done by providing this casting with two pin- 45 tles, f, one at each side, which enter recesses in a casting, g, secured to the under side of the leaf.

50 h is a slight projection cast upon the side of the casting F next to the table-leaf, which projection is designed to come in contact with the leaf, so that there will be a little space, i, be- 55 tween the remaining part of the flat portion e of the casting F and the table-leaf E. Near

the free end of the casting F is a notch, k, the walls of which stand at a slight angle, as shown in Figs. 1 and 3.

55 l is a block on C, which serves as a stop for the leaf.

60 The operation is as follows: When the leaf is down, the parts will occupy the position shown in Fig. 1, the leaf-support F resting near the bend d, upon or against the metal piece b, and the free end of the support being almost in contact with the under side of A, in which position the support F is entirely out of the way. Upon opening the leaf the leaf-support will 65 slide along over the metal piece b, the flat portion of the support near the point d being brought nearly into contact with the under side of the leaf, and when the notch comes to the metal piece b the spring action of the part e of 70 the support will cause the notch to engage quickly with b, as shown in Fig. 3, in which position the leaf will be securely held by the support F. When it is desired to put down the leaf, it is only necessary to press upward 75 upon the part e of the support until the notch is released from b, when the leaf may be allowed to fall.

75 The part e of the support has a spring action because it is comparatively thin, and because 80 the projection h comes in contact with the under side of the leaf, leaving an open space, i, between the remaining portion of e and the leaf.

85 Instead of providing the casting F with the projection h to come in contact with the table-leaf, this part might be made smooth, and a small piece of rubber or wood might be secured to the leaf between it and the part e. In Fig. 5, m is such a piece of rubber or wood, secured to the under side of the table-leaf, with which 90 the part e comes in contact when the casting F is in place, and this piece m holds the part e at a little distance from the leaf, so that the part e will have the spring action before described.

95 By constructing the leaf-support as set forth and shown the requisite spring action is inherent in the body of its straight flat portion e, intermediate the hinge and the curved portion e, whereby I am enabled to avoid the use of a separate spring between the table-leaf and the 100 leaf-support—as, for example, a coiled spring between the table-leaf and an arm of the leaf-support which extends outward beyond the pivotal point of the support.

The play or movement of the pivoted end of the leaf-support mentioned is secured by making the recesses in the casting G which receive the pintles *f* a little deeper than necessary, as indicated in the drawings.

The wall which forms the outer side of the notch *k* serves the purpose of a stop and prevents the hinges from being strained by raising the leaf too high.

10 It is customary to ship tables with the leaves open, one table being placed upon another. With our leaf-support we hold the leaves firmly in position when so shipped.

15 The spring action of the part *e* of the support *F* might be provided for by slightly curving the part *e*, so that the pivoted end will be in contact, or nearly in contact, with the leaf of the table, while the other end of *e* will be at a little distance therefrom. This form is shown 2c in Fig. 6.

If the outer wall of the notch *k* should be omitted, the leaf-support would still be useful and would have the spring action before mentioned; but it would not perform all of the 25 functions described. Its operation would be substantially the same as that specified, except that there would be no stop to prevent injury to the hinges, and, in shipping tables when placed together with the leaves open, the support would not retain its position as firmly as 30 when provided with the outer wall of the notch.

What we claim as new, and desire to secure by Letters Patent, is—

1. The combination, with a table having a hinged leaf, *E*, and a side piece, *C*, provided with a slot, *a*, and attached piece *b*, crossing the lower end of the slot, of the leaf-support *F*, formed with the curved end portion, *c*, having the notched extremity *k*, and the opposite straight and flat end portion, *e*, hinged at its 35 extremity to the leaf and formed of a reduced thickness, to produce inherent spring action in the leaf-support intermediate the hinge of the latter and the curved portion thereof, substantially as shown and described. 40

2. The combination, with a table having a hinged leaf, *E*, and a side piece, *C*, provided with an attached piece, *b*, of the leaf-support *F*, having the curved end portion, *c*, provided with the notched extremity *k*, and the opposite 50 straight and flat end portion, *e*, hinged at its extremity to the leaf and formed of a reduced thickness, to provide inherent spring action in the leaf-support intermediate the hinge of the latter and the curved portion thereof, substantially as shown and described. 55

JOHN P. WOLF.
GEORGE IFFLAND.
